FIG. 4

FIG. 5

UNITED STATES PATENT OFFICE

2,078,505

METRONOME

James H. Morrison, Los Angeles, Calif.

Application December 18, 1935, Serial No. 55,031

5 Claims. (Cl. 58—130)

My invention relates to timing devices and more particularly to an electrically actuated metronome.

An object of my invention is to provide a metronome having a constant and continuous source of power so as to overcome the necessity of winding a spring motor as is the case in the majority of metronomes in present use.

Another object of my invention is to provide an electric motor driven metronome in which the mechanism for striking beats is electrically actuated in order to reduce the power required of said motor.

A further object of my invention is to provide a metronome which is accurate and dependable in operation and yet extremely simple in construction.

Further objects and advantages will be made manifest in the following description taken in connection with the accompanying drawing in which:

Fig. 1 is a front elevational view of a preferred form of metronome of my invention.

Fig. 2 is a side elevational view of the metronome shown in Fig. 1 with one side of the housing broken away to disclose the interior of the device.

Fig. 3 is a vertical sectional view taken on the line 3—3 of Fig. 2.

Fig. 4 is an enlarged, fragmentary sectional view taken on the line 4—4 of Fig. 2.

Fig. 5 is a vertical sectional view taken on the line 5—5 of Fig. 4, and

Fig. 6 is a wiring diagram of the metronome of my invention.

Referring specifically to the drawing, a metronome 1 comprising a preferred embodiment of my invention, includes a housing 2 having a front panel 3 and a base plate 4. Mounted on the panel 3 is a bearing 5, shown in Fig. 2, in which a shaft 6 is rotatably mounted. Fixed on the shaft 6 is a dial 7 and a pinion 8. Mounted on the panel 3 below the dial 7 are switches 8, 9 and 10 as shown in Fig. 1. Switch 9 has four contact points *a*, *b*, *c*, and *d*, and switch 10 has two contact points *e* and *f* as shown diagrammatically in Fig. 6.

Extending upward from the base plate 4 are lugs 11 in which a pin 12 is fixed, the latter carrying the lower end of an oscillating arm 13. Mounted on the upper end of the arm 13 is a sector gear 14 disposed in meshing relation with the aforementioned pinion 8. Pivotedly mounted on the arm 13 by means of a screw 13a is a yoke 15 in which a shaft 16 is journaled. The yoke

15 is urged rightward, as viewed in Fig. 2 by means of a spring 17 on the screw 13a.

Fixed on the shaft 16 is a wheel 18 and contact drums 19, 20, 21, 22 and 23, each of the latter being formed to provide contact points 24 separated by segments 25 of insulating material as shown in Fig. 5. The drum 18 has 12 equally spaced contact points while the drums 20, 21, 22 and 23 have 2, 3, 4 and 6 equally spaced contact points respectively. Fixed on top of the yoke 15 is a bar 27 of insulating material in which brushes 28a, 28b, 28c, 28d and 28e are slidably mounted as seen in Fig. 4, there being wires 30a, 30b, 30c, 30d and 30e extending from the respective brushes 28a to 28e.

Secured to the base plate 4 is a housing 37 to which a synchronous electric motor 39 is fixed by means of lugs 40. Rotatably mounted on the housing 37 is a disc D, there being suitable reduction gearing within the housing 37 for transmitting rotation of the motor 39 to the disc D, the latter being driven at a relatively slow speed in the direction indicated by the arrow in Fig. 3. As shown in Fig. 2, the face of the disc D contacts the periphery of the wheel 18 and the disc moves downward relative to the wheel so that the resistance of the wheel to rotation tends to rock the yoke 15 on the screw 13a toward disc D to increase the pressure of the wheel 18 against the disc D in proportion to the amount of power required to drive the wheel 18.

Secured to the back wall of the housing 2 is a striker S comprising a bracket 43 upon which magnets 41 and 42 and a hammer 44 are mounted as shown in Fig. 2. Provided on the panel 3 above the dial 7 is a light 35, and on the side of the housing 3 is a 3-way jack 36, the purpose of which will be described hereafter.

Referring now to Fig. 6, in which I have shown a wiring diagram of the metronome 1, a suitable source of electrical current such as a battery B is shown having one lead grounded to the frame of the metronome as indicated at G. The remaining lead of the battery B is connected to the arm of the switch 10. One of the contacts *e* of the switch 10 is connected by a wire 50 to one of the receptacles of the jack 36, while the other contact *f* of the switch 10 is connected to one side of each of the magnets 41 and 42 by a wire 51. The shaft 16 upon which the drums 19 to 23 are mounted is grounded by a wire indicated at 52 thus enabling the contacts 24 of the drums to receive current from the grounded side of the battery B.

The wire 30a extends from the brush 28a of

the drum 19 to one side of the magnet 41 and the wires 30b, 30c, 30d and 30e are connected to contacts *a*, *b*, *c* and *d* respectively of the switch 9, the arm of the switch 9 being connected by a wire 53 to one side of the magnet 42. Joined to the wire 53 and extending to another of the receptacles of the jack 36 is a wire 54, the remaining receptacle of the jack 36 being connected to the wire 30a by a wire 55.

10 Suitable wires, not shown, supply electric current to the motor 39 which is controlled by the switch 8 shown in Fig. 1.

Operation

15 When the switch 8 is turned on the motor 39 is energized causing the disc D to rotate counter-clockwise as viewed in Fig. 3. The wheel 18 and drums 19, 20, 21, 22 and 23 are rotated by the disc D. The dial 7 is set so that the number indicating the desired number of beats per minute is opposite the mark indicated at M in Fig. 1. The switch 10 is then turned so that the arm thereof rests on the contact *f* thus supplying current from one side of the battery B to one side of the magnet 41, the circuit to the latter being completed each time one of the contacts 24 of the drum 19 engages the brush 28a. The intermittent supply of current to the magnet 41 causes the hammer 44 to strike the required number of beats per minute on the housing 2. When desirable to accent every sixth beat of the hammer 44 the switch 9 is set so that the arm thereof engages the contact *a* and each time one of the contacts 24 of the drum 20 engages the brush 28b 30 the circuit is completed to the magnet 42, the latter acting simultaneously with the magnet 41 to increase the velocity of the hammer 44 so as to accent every sixth beat. In a like manner every fourth, third or second beat of the hammer 44 35 may be accented by engagement of the arm of the switch 9 with the contact *b*, *c* or *d* respectively. The light 35 is connected across the wires 30a and 51 so as to flash each time the magnet 41 is energized to provide visual signals in addition to the audible signals.

40 For the purpose of providing audible and visual signals at a point remote from the metronome 1, an extension unit (not shown) is used in connection with the metronome of my invention. The extension unit comprises a housing similar 45 to the housing 2 of the metronome 1, in which a striker and light are provided, the latter being identical with the striker S and light 35 of the metronome 1.

50 Extending from the extension unit is a three wire cord 60 having a plug 61 on the end thereof as shown in Fig. 6. When the plug 61 is inserted into the jack 36 and the switch 10 positioned as shown in Fig. 6, the striker and light of the extension unit are energized in the same manner described relative to the metronome 1.

55 Although I have shown and described but one preferred form of my invention it is understood that various modifications and changes might be

made therein without departing from the spirit of the invention or the scope of the appended claims.

I claim as my invention:

1. In a metronome, the combination of: primary electrically operated means for striking audible signals; secondary electrically operated means for accenting certain of said signals; a primary power driven drum having a plurality of equally spaced contact points thereon and a brush riding on said drum for engagement with said contact points, said drum and said brush supplying intermittent charges of current to said primary means to produce a series of audible signals; a secondary drum rotatable with said primary drum; contact points on said secondary drum and a brush riding on said secondary drum for engagement with said contact points simultaneously with the engagement of certain of said contacts and said brush of said primary drum, said secondary drum supplying intermittent charges of current to said secondary means so as to accent certain of said audible signals.

2. In a metronome, the combination of: electrically operated means for striking audible signals; electrically operated means for accenting certain of said audible signals; a primary rotary switch having a plurality of contacts for intermittently energizing said signal means; a second rotary switch having one sixth as many contacts as said primary switch; a third rotary switch having one fourth as many contacts as said primary switch; a fourth rotary switch having one third as many contacts as said primary switch; a fifth rotary switch having one half as many contacts as said primary switch; power means for driving all of said switches at a common rate of speed; means for connecting any one of said second, third, fourth, or fifth switches to the circuit of said signal accenting means to accent every sixth, fourth, third or second of said audible signals.

3. A combination as in claim 2 in which control means is provided for changing the speed of said power means to cause said signal means to strike any desirable number of signals per minute.

4. In a metronome, the combination of: a hammer for striking audible signals; a magnet for actuating said hammer; means for supplying charges of current at regular intervals to cause said hammer to strike equally timed signals; a second magnet adjacent said first magnet; and means for supplying current to said second magnet simultaneously with certain of said charges supplied to said first magnet; said second magnet coacting with said first magnet to increase the velocity of said hammer to produce an accented signal.

5. In combination as in claim 4 in which switch means is provided for energizing said second magnet on every second, third, fourth or sixth beat of said hammer.

JAMES H. MORRISON.
